JOHN T. RAMSDEN, OF PHILADELPHIA, PENNSYLVANIA, ASSIGNOR TO THE TABOR
MANUFACTURING COMPANY, OF PHILADELPHIA, PENNSYLVANIA, A CORPORA-
TION OF PENNSYLVANIA

MOLDING MACHINE

Application filed November 5, 1927. Serial No. 231,308.

The present invention relates to improvements in molding machines and more particularly to hand ramming-rollover-pattern drawing molding machines for core making and for use generally.

The principal object of the present invention is to provide a machine of the type recited which can be easily and successfully operated with the employment of very little labor.

Other objects of the invention will appear from the following description and it may be said that a rollover machine of the invention is characterized by a construction in which the pattern drawing mechanism is carried by and aligned with the rollover table or frame and in which the leveling device is a provision of the clamp which is carried by the table or frame and in which there are other features of invention that will be hereinafter set forth, and at the end of this description the invention will be claimed.

In the following description reference will be made to the accompanying drawings forming part hereof and in which there is illustrated one embodiment of the invention chosen from other embodiments and in which

Figure 1 is a side elevation partly in section of a machine embodying features of the invention and in this figure the clamping head is shown as turned from a position, perpendicular to the plane of the paper, which it would normally occupy into a position, in the plane of the paper, which is its working position, for the sake of clearness.

Fig. 2 is an end view looking from left to right in Fig. 1 with a part of a counterweight indicated by dotted lines for the sake of a better illustration of the parts that lie behind it, and

Fig. 3 is a top or plan view of the machine. In the accompanying drawings 1 is a column rising from a base 2 and provided at its top with a bearing 3 and with a stop 4. 45 These parts constitute a type of supporting

structure. Hinged to the top of the column is a swinging frame generally indicated at 5. As shown this hinged connection is provided by a shaft 6 arranged in the bearing 3 and connected at its ends with the hinged frame. The hinged frame includes a table 7 shown as provided with slots 8 useful for the purpose of holding to the table any form of core boxes, pattern plates, and the like and also shown as provided with a handle 9. 10 indicates supports upon which the free end of the frame 5 rests when the machine is in ramming position. The frame 5 is provided with an arm 11 projecting oppositely from the table 7 and to which is attached one end 60 of a counterbalance spring 12, of which the other end is attached to the base 2. By moving the point of attachment of the spring 12 to the arm 11 toward and away from the end of the arm it is possible to adjust the counterbalancing effect of the spring to the weight of the core box or pattern plate. One way of doing this is by attaching the end of the spring to a pin 13 working in a slot in the arm 11 and connected with a nut 14 mounted for endwise movement on a screw 15 revolubly mounted in the arm 11 and having a finger wheel 16. The frame 5 is provided with a sleeve bearing 17 and with ears 18', Fig. 1, together constituting a holder aligned with the bearing 17. Mounted in the sleeve 17 for endwise sliding movement is the rod 18 of the clamping head generally indicated at 19. The arm 20 of this head is turnably, but endwise immovably, mounted on the rod 18, for example by means of collars 21 and 22. The arm 20 is provided with a disk 23 around which passes a spring 24 having one of its ends connected with a snail 25, and the other of its ends provided with a chain 26 of which the links are adjustably secured between the fingers 27. The snail 25 is fast on the collar 22 or otherwise secured to the rod 18. The purpose of the spring 24 is to solicit or tend to turn the arm 20 clockwise in Fig. 3. At 90

the end of the arm 20 there is mounted a cylindrical element 28 of the ball joint 29, and the element 28 is adjustable by the clamping screw 30 toward and away from the table 5 7 to accommodate flasks or core boxes of different heights. The other element of the ball joint 29 is a three-armed flask clamp 31 connected with the element 28 by means of a spring pressed bolt 32. The provisions at 10 the end of the arm 19 constitute both a clamp and a leveling device as will hereinafter more fully appear. There is fast on the rod 18 a bracket 33 having a swivel 34. The bracket 33 is provided with an eye or opening 35 through which the guide rod 36 is slideable, and the guide rod 36 is held fast in the holders 15 18'. 37 is a crank handle fulcrumed at 38 to the frame 5. Pivotedly connected to this crank handle at 39, Fig. 2, is the curved 20 portion 40 of a link that includes a rod extension 41 provided with centering springs 42 which cooperate with the bracket 33 as an abutment. 43 is a counterweight swinging on the fulcrum 38 and turnably connected 25 with the pin 39 carried by the handle or hand crank 37.

As illustrated in the accompanying drawings the machine is arranged for use as a core making machine and in describing the 20 mode of operation reference will be made to the use of the machine for making cores but it will be readily understood that the invention is applicable in molding generally.

The cavities in the core box *a* secured to 35 the frame 5 are filled with sand or like material for making cores, and the operator jars it by taking hold of the handle 9 and swinging the frame about the bearing 6 up and down against the supports 10. During 40 this operation the clamping and leveling device 31 and the arm 20 are turned downward in Fig. 3 so that they are not over the core box *a* and are not in the way. The spring 24 is a means for doing this automatically.

45 When the box *a* has been jar rammed as described it is struck off and the core plate *b* is put into position and the leveling device is turned into the position shown in Fig. 3 over the core plate *b*. Then the operator turns the hand crank 37 in the direction indicated by the arrow in Fig. 2 with the result 50 that the rod 18 of the clamping head slides toward the bearing 17 and the guide rod 36 enters the eye 44, so that the arm 20 is held against rotary motion and the clamping head is guided in a rectilinear path downward and the leveling device 31 comes into contact with the core plate. The spring transmission mechanism 42 permits further movement of 55 the handle 37 at the same time clamping the core plate and core box until the handle 37 has been turned approximately 190° into contact with the stop 45 which is a position of rest. During the described turning movement of 60 the handle 37 the counterweight 43 has been

turned upward ready for action. The operator then turns the frame 5 or rolls it over about the pivot 6 being assisted by the counterbalance spring 12 and of course the frame carries with it the core box and core 70 plate and the combined leveling device and clamp. The frame comes to rest on the stop 4. The operator then turns the hand crank 37 in the opposite direction with the result that the core box is lifted from the core plate which remains on the leveling device 31 and with the result that the eye 44 clears the rod 36, so that the leveling device 31 and the arm 20 which carries it are turned out to the side of the machine and the core plate can be removed conveniently. The spring 24 is one 75 means for turning the arm 20 in the manner described. The stops 46 and 47 limit the movement of the arm 20, and the stop 47 properly positions it for aligning the eye 44 with the rod 36. It is perhaps unnecessary to state that in drawing the pattern use may be made as is customary of a vibrator applied to the frame 5.

The handle 37 may not be turned in the direction indicated by the arrow in Fig. 2 unless the head 19 is properly positioned over the flask or mold, as shown in Fig. 3. The reason for this is that if the arm 20 be turned clockwise in Fig. 3, the stop 46 engages the handle 37 and prevents its movement in the direction of the arrow in Fig. 2. Movement of the handle 37 obviously controls the action of the spring 24 by means of the interengagement of rod 36 and eye 44. In addition to the adjustment 30 for the accommodation of flasks or boxes of different depths the spring transmission 42 is effective. Incidentally it may be said that the part 48 is a counterweight, 47 is a pin acting as a stop for aligning the eye 44 with the guide rod 36.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. A molding machine comprising a column provided with stops, a rollover frame at the top of the column and adapted to rest on the stops in pattern drawing position and to be turned into mold making position, a clamping head provided with a leveling device and slidably mounted in the frame, an operating handle carried by the frame, and mechanism between the handle and head for shifting the latter in respect to the frame to clamp and to pattern draw.

2. A molding machine comprising a rollover frame, a clamping head provided with a leveling device and movable in respect to

the frame, an operating handle carried by the frame, and spring transmission mechanism between the handle and head for shifting the latter in respect to the frame to clamp and to pattern draw.

5 3. A molding machine comprising a column provided with stops, a rollover frame turnable on the column and adapted to rest on the stops in pattern drawing position and to be turned into mold making position, a clamping head provided with a turnable leveling device and slidably connected with the frame, an operating handle carried by the frame, transmission mechanism between the handle and head for shifting the head in respect to the frame to clamp and to pattern draw, and a guide rod fast on the frame and a cooperating eye on the head.

10 4. In a molding machine a rollover frame, a clamping head slidably carried by the frame and including a turnable arm, spring means constructed and arranged to turn the arm, a guide element carried by the frame and constructed and arranged to insure alignment of the head and frame and to oppose turning movement of the arm at intermediate positions of the head, and operating means for shifting the head in respect to the frame.

15 5. In a molding machine a rollover frame, a head mounted to roll over with the frame and afforded turning motion in a generally horizontal plane, spring means tending to turn the head in such plane, guide means carried by the rollover frame and interposed between the head and frame for affording rectilinear motion of the former in respect to the latter for clamping and pattern drawing and to release the head for automatic turning motion in a horizontal plane, a leveling device having universal motion means connecting it with the head whereby it is automatically adjusted in the act of clamping, and a handle turnably connected with the frame and having spring mechanism adapted to move the head toward the frame for clamping and leveling and itself adapted to turn with the frame and then by reverse movement to separate the head from the frame for pattern drawing and for disengagement of the guide means to permit the head to swing out laterally from under the frame.

20 6. In a molding machine a rollover frame, a head mounted to roll over with the frame and afforded turning motion in a generally horizontal plane, spring means tending to turn the head in such plane, guide means carried by the rollover frame and interposed between the head and frame for affording rectilinear motion of the former in respect to the latter for clamping and pattern drawing and to release the head for automatic turning motion in a horizontal plane, and means connected with the frame and adapted

25 to move the head and to disengage and re-engage the clamping means.

7. In a molding machine a rollover frame, a head mounted to roll over with the frame and afforded motion in respect thereto, a leveling device having universal motion means connecting it with the head whereby it is automatically adjusted in the act of clamping by movement of the head, and means for moving the head in respect to the frame.
